UNITED STATES PATENT OFFICE.

MYRON A. ROSS, OF MORGANTOWN, WEST VIRGINIA, ASSIGNOR TO PRESSED PRISM PLATE GLASS COMPANY, OF MORGANTOWN, WEST VIRGINIA, A CORPORATION OF WEST VIRGINIA.

PLATE-GLASS DEVICE.

1,075,793.

Specification of Letters Patent.

Patented Oct. 14, 1913.

Application filed July 31, 1912. Serial No. 712,446.

To all whom it may concern:

Be it known that I, MYRON A. ROSS, a citizen of the United States, residing in Morgantown, in the county of Monongalia and State of West Virginia, have invented a new and useful Improvement in Plate-Glass Devices, of which the following is a specification.

This invention relates to improvements in plate glass devices.

An object of the invention is to provide a plate glass device adapted for illuminated, display, changeable sign use, particularly of large size, and in which the letter, numeral, emblem or other symbol is formed with sharp, clear outlines and integrally with the plate, the entire glass-mass being substantially homogeneous throughout.

Another object is to provide a plate glass device, the entire mass of which is homogeneous throughout, having the letter, emblem or other symbol in protuberant relief, relatively thick as compared to the thickness of the plate, the raised portion being preferably one and one half, or even more, times as thick as the plate, thus distributing the glass-mass at the places where most desired, and effecting a large saving in the cost of material and reducing the weight of the finished article.

Another object is to provide a plate glass device of the type above indicated, in which each symbol, *per se*, is lens-formed, making with the plate a substantially plano-convex lens adapted to disperse and distribute the light rays after passing through the glass, the convex portions being also fluted longitudinally to thereby sub-divide the larger lens into a plurality of smaller lenses for the purpose of giving substantial width to the shaft of light as it emerges or is reflected from the device.

The invention furthermore consists in other features of improvement hereinafter disclosed and set forth in the claims.

I am aware of pressed glass devices having letters thereon, suitable for sign use, which have been formed with the relief portions molded integrally with the base portions, and of other types in which the letter is made separately from the plate and applied thereto by fusing, cementing or otherwise. Still another type of such devices is that in which the portions of the glass-mass

composing the numeral and the base have different characteristics, although both portions are molded together into a single piece.

It has been found that the aforesaid devices in which the letter is made separately are commercially impracticable, since not only is the first expense of manufacturing them prohibitive, but in use, they rapidly deteriorate when subjected to wind, rain and other elements. The aforesaid signs in which two different kinds of glass are used are not only exceedingly expensive to manufacture, due partly to the use of two kinds of glass, and partly to the necessity of molding one portion at a time and fusing the two portions together, but are limited in size to less than four inches in height and width, there being no known successful process of treating glass by molding or pressing only, where the glass-mass has a depth of more than about four inches, since the mass in cooling and contracting will crack and form irregularities in the surface. This is true also of the molded type of sign letters first mentioned in the last preceding paragraph, the letters being limited in manufacture to a height not over about six inches, nor has it ever been possible by molding or pressing, only, to obtain glass sign-letters having a thin base, and relatively thick relief in larger sizes than about six inches because of the thinness of the base on which the letter is molded.

All of the types of glass devices disclosed by the prior art known to me, showing the letter or numeral and the base formed integrally, are of such formation that the possibility of manufacturing them by any other method than mere molding or die pressing is precluded, and where the letter and the base portion are formed integral, the size is limited in height to six inches or less.

In the drawing forming a part of this specification, Figure 1 is a plan view of a plate glass device embodying my improvements. Fig. 2 is a side elevation of the structure shown in Fig. 1, and Fig. 3 is an enlarged, detail sectional view, approximately full size, and taken substantially on the line 3-3 of Fig. 1.

In the drawing, 10 denotes a rolled, rectangular plate or sheet of glass having a plane back surface, and which, as shown, is provided with a single, raised, solid symbol

11, formed integrally with the plate, the glass-mass of both members being substantially homogeneous throughout. The particular symbol shown in the drawing is the letter "F", but as will be understood, other letters of the alphabet, or punctuation marks, numerals, emblems or other symbols could be formed, without departing from the spirit of the invention. Each portion of the 5 raised symbol 11 is substantially lens-formed, and is provided with a plurality of convex flutes or ribs 12, arranged longitudinally of each portion of the symbol. The plate shown in the drawing has only one symbol 10 on it and is adapted to be used in combination with a number of other plates, each having other symbols thereon, for use in making up illuminated display signs, the letters of which are approximately one foot 15 in height, although, as will be obvious, a single plate of glass may be made with the several letters thereon to form a word, if desired, thus having a single plate for the entire sign, which is strong, durable and 20 light.

Where a smooth, convex surface only is used for the raised symbols, the light appears to an observer at a distance to be transmitted therethrough in single lines or planes, so that the 25 observer receives the impression of a letter or other symbol having only line outlines, but by fluting the convex surface in the manner shown and described, the convex surface or lens is subdivided into a plurality of 30 small, parallelly arranged, convex surfaces or lenses, through each of which light is transmitted to an observer in a line or plane, thus causing the letter, numeral or other symbol to appear solid and to have substantial width. The above described effect occurs no matter at what angle the observer 35 looks at the illuminated sign, and not only is this true where light is transmitted through the glass plate devices, as at night, but also in the daytime light is reflected from the letter, numeral or other symbol to the observer in a wide shaft instead of in a single line or plane, and by having the symbols of such relatively great height and in 40 protuberant relief, the outlines of the letters or other symbols can easily be distinguished even at very oblique angles to the sign and from great distances. The plane back surface of the plate may be sandblasted or ground, as shown in the drawing 45 at 13, in order to prevent the source of light from showing through the plate, and if desired the plate may also be provided with an opaque coating of paint 14, both for decorative purposes and where desired, to entirely 50 prevent the light from being transmitted through the plate except at the desired portions.

The following is a suitable, and the preferred, method of manufacture of the de-

vice: In my process I first form a sheet of plate of glass preferably by placing a gathering of glass on a platen and reducing it to plate form in a state of what I term homogeneous consistency and molecular arrangement, as by rolling or equivalent operation. In practice this is preferably done by rolling the glass while freely plastic, in the well known manner, and then while the plate is on a platen,—which may or may not be the platen upon which the gathering is rolled,—apply pressure in a direction transverse to the plate on portions located outside of the periphery of the letter or other symbol formed on the plate, and thus decrease the thickness of the plate at the portions where the pressure is applied, and cause portions of the glass-mass to flow toward the center or part of the plate where the letter or other symbol is located, the flow of the glass-mass taking place in paths substantially paralleling the surface of the plate and convergent toward the part where the letter or other symbol is formed, so that portions of the glass-mass are then forced up 70 into and completely fill a deep recess in a die corresponding to the letter or other symbol desired. During this operation the edges of the plate may be confined as found desirable. In practice they are or may be self-confined 75 by the less viscosity of the sheet at or near its somewhat cooler outer edges, which impedes the outward flow of the glass and causes it to flow inward and into the recess of the die. The plate with the letter or 80 other symbol formed integrally therewith is then allowed to chill slightly to cause it to set sufficiently to be able to retain its shape, after which the plate glass device is annealed in the ordinary manner.

In practising my invention, I may make the plate comparatively thin and the symbols, formed integrally therewith, relatively thick, and the height of the letters, numerals or other symbols may range from about eight 85 to eighteen inches, and may be made even higher. If desired, the number of letters, numerals or other symbols on a single plate 90 may be increased or multiplied so as to form, for instance, a complete word, such as the 95 word "Drugs", or any common, stock sign-word or a series of numerals, the size and characteristics of the finished article being limited only by the size of the rolled plate 100 on which the symbols are formed, which can, in actual practice, be made as large as sixty 105 by ninety-six inches, the finished plate having a thickness of approximately five-sixteenths of an inch, and the solid symbols being approximately a further one-half inch 110 in thickness.

I claim:

1. A sheet of glass of homogeneous consistency and molecular arrangement in substantially the form of plate glass, having 115

embossed on the surface thereof in protuberant relief a symbol composed of glass flowed in various directions and various amounts from the body of and raised from and integral with the sheet, substantially as specified.

5 2. A sheet of glass of homogeneous consistency and molecular arrangement in substantially the form of plate glass, having embossed on the surface thereof in protuberant relief a letter composed of glass flowed in various directions and various amounts from the body of and raised from and integral with the sheet, and formed with substantially parallel flutes to give approx- 10 parent width and body to the parts of the letter, substantially as specified.

15 3. A sheet of rolled plate glass having embossed on the surface thereof in protuberant relief a symbol composed of glass flowed in various directions from the body of and raised from and integral with the sheet, substantially as specified.

20 4. A sheet of rolled plate glass having embossed on the surface thereof in protuberant relief a symbol composed of fluted glass flowed and raised from the body of the rolled sheet and integral therewith, substantially as specified.

25 5. A sheet of rolled plate glass having a

symbol in protuberant relief embossed on one surface thereof composed of glass flowed from and integral with the body of the sheet irrespective of the formation of the other surface of the sheet, substantially as specified.

30 6. A sheet of glass of homogeneous consistency and molecular arrangement in substantially the form of plate glass, having on the surface thereof in protuberant relief a symbol composed of glass flowed in various horizontal and convergent directions and distances in the plane of the sheet and in various amounts from different parts of the body of the sheet, and up from and integral with the sheet, substantially as specified.

35 7. As an article of manufacture, a sheet having a symbol integrally embossed thereon in protuberant relief composed of successively rolled and pressed glass, substantially as specified.

40 In testimony whereof, I have hereunto set my hand in the presence of two subscribing witnesses.
